UNITED STATES PATENT OFFICE.

MATTHIAS R. LONGACRE, OF MILLERSTOWN, PENNSYLVANIA.

RAILWAY.

No. 872,831.

Specification of Letters Patent.

Patented Dec. 3, 1907.

Application filed January 19, 1907. Serial No. 353,104.

To all whom it may concern:

Be it known that I, MATTHIAS REIFF LONGACRE, a citizen of the United States, residing at Millerstown, in the county of Perry and State of Pennsylvania, have invented certain new and useful Improvements in Railways, of which the following is a specification.

My invention consists of an improved railway, the roadbed superstructure upon which the rail rests, and to which the rail is secured being sectional sills formed of concrete or cement, with an outside casing of metal constituting a mold for the concrete or cement, 10 having metal bands secured thereto suitably constructed with rail chairs for securing the rails to the sills. The top of the said bands forming the rail chairs may be insetted in the surface of the sill so that the base of the rail 15 rests flush with the surface of the chair and sill, preferably for steam service the top of the band forming the rail chair resting on the surface of the sill, or on a cushion pad insetted in the top of the sill forming a space 20 between the base of the rail and the top of the sill for the easy riding of the rail.

The sectional sills are firmly tied together lengthwise by flanges formed on the ends of the metal casing bolted or riveted together, 30 and are held in alignment by tie-rods secured to the sills extending laterally from one sill to the sill opposite. The rails are secured thereto dispensing with railroad ties; the sectional sills thus formed and secured together 35 are embedded in a suitable composition, concrete, cement, or ballast, forming a substantial foundational structure for the rails greatly increasing safety, durability, and efficiency of the railway; I attain these objects by the construction as illustrated by the accompanying drawings.

In the accompanying drawings Figure 1, is a perspective view of a portion of railroad illustrating my improved railway; Fig. 2, is a top view of one of the sectional sills; Fig. 3, is a side view; Fig. 4, is a cross sectional view in the line 1; 1, Fig. 1; Fig. 5, is a perspective view of one of the sill bands; Fig. 6, is a perspective view of the separate parts of 50 the sill bands; Fig. 7, is a perspective view of a sill band for securing the ends of the rail together, similar letters referring to similar parts throughout the several views.

"A" represents the sectional sills formed 55 of concrete or cement preferably of concrete molded in metal casings having bands se-

cured thereto suitably formed with rail chairs for securing the rails to the sills, the said sills tied together lengthwise by the flanges "F", formed on the ends of the metal casing riveted or bolted together and in alignment by tie rods "G" extending laterally from one sill to the sill opposite, the sills thus tied together, embedded in a suitable composition, cement, concrete, or ballast, forming a substantial foundation structure for the rails, dispensing with the use of railroad ties.

"B" represents the concrete molded in the metal casing "C", having chair cushion pads "m'" insetted therein flush with the surface of the sills the cushion pads being rounded so that the arched top of the sill bands forming the rail chair "L", may be seated in the corresponding recesses of casing "C".

"C" represents the metal casing forming molds for the concrete filling "B" the said metal casing being made in convenient lengths and of suitable girth of sheet metal or steel plates pressed into shape or riveted together and may be trapezoid or square preferably square or rectangular, having recesses conforming to the recesses "m'" in the concrete filling for insetting the sill bands "D" and facilitating the replacing of cushion pads "m'" the ends of the casing having flanges "F" with corresponding holes "f" for bolts or rivets to secure the ends of the sill "A" together end to end.

"D" represents the sill bands suitably formed with rail chairs for securing rails "R" to the sills "A", the said bands formed in two parts hinged or looped together by the thong "i" linked into the loop "i" forming a clamp device, the sill bands being secured to the sills by the tie rod "G" the threaded ends "g'" passing through a hole in the sill in line with the hole "h" in the band, the nut "g'" clamping the band to the sill being locked thereto by the lugs "n'" formed on the bands, fitting into the recesses "n'" in the sill, the nut "g'" at the same time clamping the rail "R" in the clips d' d' the arched top of the sill band resting on the cushion pad "m'" the rail "R" seated on the seats e' e' forming a space "S" between the base of the rail and the top of the sill for the easy riding of the rail; the sill bands may be secured to the sills independent of the tie rod "G" when the curvature of the road, or other conditions of construction make it necessary.

2
 "E", Fig. 7, represents a sill band in modified form for securing the ends of the rails "R" together end to end with the clip plates "c", one on either side of the rail and the 5 ends of the rails securely bolted together.

The tie rods "G" are secured together by a turn buckle "g'" the tie rod thus formed being secured to the sill by the bolt "g" the head of the bolt "t" being shaped so as to 10 be held with a wrench or it may be locked or slotted into the sill or sill band to prevent turning, the turn buckle "g'" facilitating the ready setting and adjusting of the sills in alinement. The sills when finally set are 15 embedded in a plastic substance concrete, or cement, preferably in the ordinary ballast of the road the whole forming a desirable foundation structure for the rails securing greater safety and comfort, rapid and inexpensive 20 construction.

Having now described my invention what I claim as new, and desire to secure by Letters Patent is:

1. A railway having sectional sills lengthwise or parallel with the rails for supporting the rails, formed of concrete molded in metal casings having bands reinforcing the sills and forming rail chairs for supporting and securing the rails to the sills, suitably tied together, embedded in filling. 25

2. A railway having sectional sills formed

of concrete molded in metal casings, the ends of said casings formed with flanges bolted together, securing the sills together lengthwise, and bands secured to the sills provided with 35 rail chairs securing the rails to the sills.

3. A railway having sectional sills formed of concrete molded in metal casings, bands supporting and securing the rails to the sills which are tied together lengthwise, and held 40 in alinement by tie rods secured to the sills, extending laterally from one sill to the sill opposite forming cross ties.

4. A railway having sectional sills supporting the rails, said sills formed of concrete in 45 metal casings, and bands with arched tops forming rail chairs resting on cushion plates with open space between the base of the rail and sill.

5. A railway having sectional sills formed 50 of concrete in metal casings, and bands forming rail chairs formed in two detachable parts clamping the rails to the sills.

6. A railway having sectional sills suitably tied together formed of concrete in metal casings, and bands forming rail chairs provided with plates securing the ends of the rails together. 55
